HANDLE FOR A HEATING TORCH

John W. Meese, Avon, Ohio, assignor to Emerson
Electric Co., St. Louis, Mo.

Filed July 20, 1970, Ser. No. 24,025

Term of patent 14 years

Int. Cl. D8—05

U.S. Cl. D8—30

Fig. 1

Fig. 2

Fig. 3

Fig. 4

Fig. 5

Fig. 6

Fig. 7

FIG. 1 is a side elevational view of a reduced scale of the handle for a heating torch showing my new design, with a propane heating torch and fitting being shown in broken lines for illustrative purposes only;

FIG. 2 is a full sized elevational view of the handle;

FIG. 3 is a view from the upper side;

FIG. 4 is a top plan view;

FIG. 5 is a bottom plan view;

FIG. 6 is an end elevational view from the left end as viewed in FIG. 2; and

FIG. 7 is an end elevational view from the opposite end.

I claim:

The ornamental design for a handle for a heating torch, as shown and described.
